UNITED STATES PATENT OFFICE.

EDWARD NEVILLE VOSE, OF DARIEN, CONNECTICUT.

RUNNING-BOARD MAT.

Application filed April 3, 1924. Serial No. 704,054.

To all whom it may concern:

Be it known that I, EDWARD NEVILLE VOSE, a citizen of the United States, and a resident of Darien, in the county of Fairfield and State of Connecticut, have invented a new and Improved Running-Board Mat, of which the following is a full, clear, and exact description.

This invention relates to improvements in running board mats and more particularly to a mat designed as an attachment for the running board or step of an automobile and which is hingedly connected thereto so that it can be readily positioned on the upper face of the running board or step and can also be swung under the running board or step and held in this last-named position until desired for use.

An object of the invention, therefore, is to provide a running board mat which may be normally supported under the running board out of sight and out of the way, and protected from ordinary wear, but which can be easily and quickly swung into position on the upper face of the running board when desired for use.

With these and other objects in view, the invention consists in certain novel features of construction and combinations and arrangements of parts which will be more fully hereinafter described and pointed out in the claims.

In the accompanying drawings—

Figure 1 is a perspective view illustrating my improved mat in operative position on the upper face of the running board of an automobile;

Figure 2 is a view in transverse section through the mat and running board;

Figure 3 is a view similar to Figure 2, showing the mat supported against the under face of the running board, this section being taken on the line 3—3 of Figure 4;

Figure 4 is an inverted plan view of the running board showing the position of the mat when supported against the under face of the board;

Figure 5 is a perspective view of one end of the mat showing its connection to the running board.

For purposes of illustration I have shown an automobile 1 provided with the ordinary type of running board 2, although it is, of course, to be understood that this invention is not limited to any particular type

of automobile or vehicle or to any particular construction of running board or step.

3 represents my improved mat which may be of any suitable material and is preferably strengthened by a metal border 4 of general channel shape in cross section. The ends of this metallic border are pivotally connected as shown at 5 to leaves 6 of a hinge 7, the other member or leaf 8 of the hinge being rigidly secured to the under face of the running board. This leaf 8 preferably constitutes a relatively large metal plate which is fixed to the under face of the running board and constitutes a wear plate for the mat when the latter is against the under face of the board.

I would call particular attention to the pivotal connection 5 between the mat and the hinge leaf. This construction embodies an angle bracket 9 which is fixed to the leaf 8 and located at right angles thereto, one end or member of the angle being pivotally connected to the mat, as shown at 5, and the other end 10 of the angle being located against the inner edge of the mat under normal conditions. By reason of this hinge and pivotal construction above described it will be noted that the mat may be swung to a position above the running board as shown in Figure 2 or to a position under the running board as shown in Figure 3.

When on the running board the metallic frame or border portion 4 is preferably supported on angular cushion blocks 11, as clearly shown in Figure 2. When the mat is swung into position under the running board it is caught and held by a latch finger 12 on a metal strip 13 which is mounted to slide transversely of the plate 8 in suitable guides 14. At the forward end of the strip 13 an operating handle 15 depends from the strip and is preferably formed by bending the end of said strip, and a wire spring 16, fixed to the plate 8 at its ends, engages this handle 15 at its intermediate portion to normally press the latch finger into engagement with the mat.

To release the mat it is simply necessary to force the handle 15 inwardly thus pressing the latch finger 12 away from the mat and allowing the mat to fall to substantially vertical position, where it can be easily grasped and swung over on top of the running board. When the mat is swung back under the running board it will engage the finger 12 and snap into holding position.

It will thus be noted that I provide a mat which can be positioned under the running board and be out of the way and out of sight but can be brought into operative position on top of the running board whenever desired.

Various slight changes and alterations might be made in the general form of the parts described without departing from my 10 invention, and hence I do not limit myself to the precise details set forth but consider myself at liberty to make such slight changes and alterations as fairly fall within the spirit and scope of the appended claims.

15 I claim:

1. A mat for running boards, comprising a hinge, one member of the hinge adapted to be connected to the running board whereby the mat may be positioned either on top 20 or against the underface of the running board, and means for holding the mat in its last-named position.

2. A mat for running boards, comprising a hinge, one member of the hinge adapted 25 to be connected to the running board whereby the mat may be positioned either on top or against the under face of the running board, means for holding the mat in its last-named position, said means embodying a 30 spring held latch member, and a handle adjacent the outer edge of the running board for operation of the latch.

3. The combination with a running board, a mat hingedly connected to the outer edge of the running board adapted to be swung 35 into position on top of the running board or into position under the running board, a spring held strip at the under face of the running board, a latch finger at the inner edge of the strip adapted to engage the mat 40 and hold it under the running board, and a depending handle at the outer end of the strip.

4. The combination with a running board, a hinge connected to the outer edge of the 45 running board, a mat pivotally connected at its ends to one leaf of the hinge and adapted to be swung into position on top of the running board or into position under the running board, and cushion blocks on the running board supporting the edge of the mat 50 when the latter is thereon.

5. The combination with a running board, a hinge connected to the outer edge of the running board, a mat pivotally connected at 55 its ends to one leaf of the hinge and adapted to be swung into position on top of the running board or into position under the running board, and cushion blocks on the running board supporting the edge of the mat 60 when the latter is thereon, said mat having a metal border and said metal border constituting a strengthening frame for the mat.

EDWARD NEVILLE VOSE.
